(57) **CLAIM**

The ornamental design for a automotive plaque for solar rays with fins and hole for suction pad, as shown and described.

DESCRIPTION

FIG. 1 is a perspective view of a first embodiment of the automotive plaque for solar rays with fins and hole for suction pad

FIG. 2 is a left lateral view of the first embodiment of the automotive plaque for solar rays with fins and hole for suction pad

FIG. 3 is a right lateral view of the first embodiment of the automotive plaque for solar rays with fins and hole for suction pad

FIG. 4 is a bottom view of the first embodiment of the automotive plaque for solar rays with fins and hole for suction pad

FIG. 5 is a top view of the first embodiment of the automotive plaque for solar rays with fins and hole for suction pad

FIG. 6 is a rear view of the first embodiment of the automotive plaque for solar rays with fins and hole for suction pad

FIG. 7 is a front view of the first embodiment of the automotive plaque for solar rays with fins and hole for suction pad

FIG. 8 is a perspective view of a second embodiment of the automotive plaque for solar rays with fins and hole for suction pad

FIG. 9 is a left lateral view of the second embodiment of the automotive plaque for solar rays with fins and hole for suction pad

FIG. 10 is a right lateral view of the second embodiment of the automotive plaque for solar rays with fins and hole for suction pad

FIG. 11 is a bottom view of the second embodiment of the automotive plaque for solar rays with fins and hole for suction pad

FIG. 12 is a top view of the second embodiment of the automotive plaque for solar rays with fins and hole for suction pad

FIG. 13 is a rear view of the second embodiment of the automotive plaque for solar rays with fins and hole for suction pad

FIG. 14 is a front view of the second embodiment of the automotive plaque for solar rays with fins and hole for suction pad

FIG. 15 is a perspective view of a third embodiment of the automotive plaque for solar rays with fins and hole for suction pad

FIG. 16 is a left lateral view of the third embodiment of the automotive plaque for solar rays with fins and hole for suction pad

FIG. 17 is a right lateral view of the third embodiment of the automotive plaque for solar rays with fins and hole for suction pad

(Continued)

FIG. 18 is a bottom view of the third embodiment of the automotive plaque for solar rays with fins and hole for suction pad

FIG. 19 is a top view of the third embodiment of the automotive plaque for solar rays with fins and hole for suction pad

FIG. 20 is a rear view of the third embodiment of the automotive plaque for solar rays with fins and hole for suction pad; and,

FIG. 21 is a front view of the third embodiment of the automotive plaque for solar rays with fins and hole for suction pad.
